UNITED STATES PATENT OFFICE.

ALEXANDER BEVAN, OF PROVIDENCE, RHODE ISLAND.

SURFACING-MACHINE.

979,739.

Specification of Letters Patent. Patented Dec. 27, 1910.

Application filed May 20, 1907. Serial No. 374,560.

To all whom it may concern:

Be it known that I, ALEXANDER BEVAN, a citizen of the United States, residing at the city of Providence, in the county of Providence and State of Rhode Island, have invented certain new and useful Improvements in Surfacing-Machines, of which the following is a specification, reference being had therein to the accompanying drawing.

10 This invention relates to improvements in surfacing machines, which consist chiefly in providing a power driven roll covered with readily detachable abrasive or polishing material, and mounted in such a manner as to 15 automatically adjust itself to the contour of the surface over which it is moved to produce the desired results.

The machine is especially designed to operate on old or new floors for the purpose 20 of cleaning, smoothing or polishing the same effectively and economically according to the varying requirements. It may also be successfully employed to produce a plane, smooth and level surface on bowling alleys, 25 if desired. As all ordinary floors vary more or less from a plane or flat surface, owing to imperfect matching, irregularities of the supporting timbers, etc., it has been found desirable, in order to operate rapidly and 30 economically in cleaning and smoothing floors, to provide means whereby the operating roll will automatically adjust itself to the irregularities of the floor, independent of the motor carriage. Economy and effi- 35 ciency in operation are obtained also by the novel and effective means of securing the abrasive covering around the roll.

An important feature of the invention is the improved construction of the receptacle 40 or roll casing which is provided for collecting the dust and waste material resulting from the work of the machine.

A further object of the invention is to provide an attachment whereby a plane and 45 level surface on bowling alleys and the like may be produced.

Other novel and useful features will be described and illustrated in the accompanying drawings, and then included in the ap- 50 pended claims.

Like characters designate corresponding parts in all the views.

Figure 1— is a plan view of the device showing a portion of the roll casing broken

away. Fig. 2— is a side elevation of the 55 device omitting the driving mechanism showing the roll casing in section. Fig. 3— is an enlarged central sectional side elevation through the pivot pin. Fig. 4— is a longitudinal section of the operating roll and 60 bearings on the vertical line through its axis. Fig. 5— is an enlarged end elevation of the two clamping jaws. Fig. 6— is a front elevation of an attachment to my de- 65 vice for leveling the floor of a bowling alley. Fig. 7— is a side elevation of the same.

Referring to the drawings at 1 is a frame mounted on wheels 2—2 forming a suitable truck for carrying the motor 3. At 4 and 5 are two forwardly extending offset bars pivoted at one end to the motor bearings at 6—6. Bolted to the opposite end of these offset bars are the short plates 7 and 8, which plates are connected together by the cross bars 9 and 10. The bolt holes 7^a 70 through these bars are elongated for the purpose of adjusting said plate endwise thereon to regulate the tension of the motor driving belt. The forwardly extending pivot pin 11 is connected to these cross bars. At 12 and 13 are forwardly extending arms connected together by the cross bars 14 and 15, the whole forming a frame for supporting the dressing roll hereinafter described. One end of each of these arms 12 and 13 is 75 notched out at 16—16 at its upper edge to receive a corresponding projecting portion 17 on the plates 7 and 8 forming overlapping portions to limit the swiveling motion 80 of the roll frame. The end of each of the plates is slotted at 18—18 to receive a ball 19—19 which serves as a bearing to take the pressure due to the pull of the driving belt and at the same time to permit of an easy 85 swiveling motion of the roll frame on the pivot pin 11. The purpose of this construction is to afford the flexibility necessary to allow the dressing roll to automatically adjust itself to readily follow any slight in- 90 equalities in the floor.

Set-screws 21—21 are threaded through the frame whereby said frame may be locked against a swiveling motion when it is required to produce a plane or flat surface instead of simply cleaning or smoothing the same. The swivel pin 11 extends forward through the said cross bars 14 and 15 whereby the extension arms and roll supporting 100 105

frames are pivotally joined to the cross bars 9 and 10, and loosely secured in position by means of the nut 20, which is threaded onto said pivot. The ends of these arms 12 and 13 are provided with slotted portions 22 for the reception of the dressing roll bearings 23. A cotter pin 24, or the like, may be passed through the ends of these arms to prevent the bearings from dropping out. 10 when the driving belt is not in position on the shaft to hold the same in place.

The dressing roll 25, see Fig. 4, is constructed of a cylinder provided at each end with a head 26—26 fitted tightly therein, the 15 whole being mounted on a shaft 27 which extends through and is fixed to both heads. Bearing blocks 23—23 are fitted onto said shaft at each end thereof, each of said blocks being provided with an annular groove 20 28—28 for the reception of the forked ends of the extension arms 12 and 13, and the edges of the slotted portion 43 of the dust guard are adapted to fit into the annular grooves 29—29 which are also formed in 25 said bearings.

A longitudinal slot 30 is cut through the shell of the roll into which the ends of the cutting or polishing material are passed to be engaged by the jaws 31 and 32 of the 30 holding clamps. Within the roll on one side of the slot 30 is a spring clamp 33 which may be pressed inward by the push button 34 to allow one end of the abrasive material to be passed between it and the inside of the 35 roll. This abrasive material is then wrapped around the roll and its opposite end is secured between the two jaws of the clamp which automatically operate to hold it tightly around the roll and take up any 40 slack due to stretching or yielding of the same. This automatic clamping mechanism consists of the said main jaw 31 rotatably mounted in bearings in the cylinder heads, and an auxiliary jaw 32 rotatably mounted 45 on the axle of the main jaw. Around this axle are two coiled springs 35, one end of each being secured to said axle and the other end of each to a fixed support, whereby the tension of the same serves to rotate the jaws 50 to tighten the material around the roll. The auxiliary jaw 32 is rotatably secured to the main jaw 31 by a pair of rings 35^a, each ring is provided with a finger 36. Extending around from the back side of the main 55 jaw to the back side of the auxiliary jaw is a flat spring 37, the tension of which serves to close said jaws together. When it is desired to open these jaws a key or other suitable operating handle is inserted into 60 the recess 38 in the axle and by turning the same to the left against the tension of springs 35, the fingers 36 on rings 35^a meet the stop pins 39 causing the two jaws to separate, and permitting the insertion of one 65 end of the abrasive material, which will be

clamped and held firmly upon releasing the main jaw, all looseness and slack being at once taken up by the tension of springs 35.

The dust and waste collector is preferably constructed of sheet material and made in 70 two parts, a rectangular holder 40, and a cylindrical hood 41, said parts being held together when in place by spring clasps 42, or other suitable means for readily connecting and disconnecting the same. These 75 spring clasps are preferably made of thin sheet steel firmly riveted at 46 to the hood, the lower end of each being provided with a pin 47 which extends through the hood and into a corresponding hole in the holder. As 80 many of these spring clasps may be provided as required to hold the sides of the hood and holder in position. When it is desired to remove the hood or the holder the lower ends of the spring clasps are simply 85 drawn outward completely disengaging the two parts which may then be readily removed.

Slots 43 are formed in the ends of hood 41, the edges thereof being designed to engage grooves 29 formed in the bearings 23. When the holder 40 is secured in position, the top edges of the end walls thereof are located a very short distance below said 95 bearings 23, as shown. In this manner the hood is free to rock upon bearings 23 and at the same time a slight vertical movement is also permitted, whereby the dressing roll is allowed to conform to any inequalities in the surface being acted upon. A longitudinal opening 44 is also formed in the bottom of the holder 40 of sufficient width and length to allow the roll to work there-through, and provide a proper clearance around the same. Inclining upward from 100 either side of this slot 44 are inwardly extending shelves 45—45 which serve to form pockets to receive and retain all waste material cut away by the operating roll. The lips of this holder are shown as being in contact with the surface acted upon so as to more effectively gather up the waste material as they are moved along the surface. The advantage of this two part construction is that these shelves may be brought close 110 to each other and to the point of contact of the dressing roll, whereby the dust and material removed from the surface or floor will be "drawn" through the narrow space between the roll and over the shelf into the 115 pocket by the "suction" due to the rapid motion of the roll.

At 60 is a forwardly extending resilient bar on which is adjustably mounted a 120 weight 61, which serves the double purpose of regulating the pressure of the dressing roll on the floor and of checking any tendency of the roll to vibrate. The bar is made resilient so that the weight thereon may 125 vibrate out of harmony with the vibrations of 130

the roll, whereby the vibrations of both are mutually checked, thus causing the roll to run smoothly upon its working surface. This weight is adapted to be moved either 5 forward or back to regulate the pressure of the operating roll upon the floor.

At 62 is a bar fixed to the motor truck at 63, its opposite end being arranged to pass loosely through a slot in the cross bar 15 10 whereby the roll may be raised from the floor by pressing down the operating handle when desired.

It is found in practice very desirable in 15 floor finishing machines to be able to finish the floor of bowling alleys absolutely level, and I have therefore provided a leveling attachment for my machine which consists essentially of members 49—49 mounted to move parallel with the bowling alley on 20 wheels 50—50 which roll on the tracks 51—51. A transverse cross bar is supported from these members at either end by the frames 53—53. The hangers 54—54 are suspended from this transverse bar by the 25 wheels 55—55 and are connected to the roll arms 12 and 13 and are thus adapted to carry this operating roll transversely across the face of the alley to be finished. It will be seen by this construction that the operating 30 roll is guided lengthwise of the alley on the tracks 51—51 and transversely across the alley on the bar 52. Suitable means for vertical adjustment of the roll, not shown, are provided whereby the engagement of the 35 same with the floor may be nicely adjusted. It will be seen that by the use of a device of this construction a floor may be finished absolutely level.

In the operation of my improved floor 40 finishing machine the truck on which the motor is carried is provided with an operating handle 56 which is pivoted to the wheel axle 57 and is provided with a rest pin 58 which may be caused to engage 45 the truck so that by pressing down on the operating handle the forward end of the truck and the operating roll may be lifted from the floor through its flexible connecting member 62. This operating roll is preferably 50 driven from the motor by two belts, one at each end thereof, one belt, 59, only, however, being shown in these drawings.

My improved floor finishing machine is of 55 a simple and practical construction and by means of its swiveling frame it will automatically follow the contour or unevenness in the surface operated upon and thereby render a machine of this character very effective where rapid cleaning and smoothing 60 is desired, rather than a level surface.

Having thus described my invention, what I claim as new and desire to secure by Letters Patent, is:

1. In a surfacing machine, the combination 65 of a truck, a motor carried by said truck,

a frame axially hung from said truck, a dressing roll mounted in said frame whereby said roll may have a vertical motion independent of that of said truck, means for driving said roll from said motor, and 70 means whereby the axis of the roll may swing out of a line parallel with the axis of the shaft on which the same is pivotally hung.

2. In a surfacing machine, the combination 75 of a truck, a motor carried by said truck, a frame rotatably hung at one end on the motor shaft bearings, a dressing roll mounted in the opposite end of said frame, a belt for transmitting a rotatory motion from 80 said motor to said roll, and means whereby the axis of said roll may be free to swing out of a line parallel with the axis of the driving motor shaft.

3. In a surfacing machine, the combination 85 of a truck, a motor carried by said truck, a frame pivotally connected to said truck, said frame being constructed in two parts and connected together by a swivel pin whereby one portion may oscillate on 90 the other, a dressing roll mounted in the oscillating portion of said frame, and means for driving said roll from said motor.

4. In a surfacing machine the combination 95 of a truck, a motor carried by said truck, a frame pivotally connected to said truck, said frame being constructed in two parts and connected together by a swivel pin whereby one portion may oscillate on the other, means also in said frame for preventing said oscillating motion, a dressing roll mounted in the oscillating portion of said frame, and means for driving said roll from said motor.

5. In a surfacing machine the combination 105 of a truck, a motor carried on said truck, a frame pivotally hung at one end on the motor shaft bearings, a dressing roll mounted in the opposite end of said frame, a belt for transmitting a rotatory motion from said motor to said roll, said frame being constructed in two parts and connected together 110 by a swivel pin whereby one portion may oscillate on the other, and means in said frame whereby the strain of the driving belt is received and the oscillating motion facilitated.

6. In a surfacing machine, the combination 115 of a motor, a motor truck, a dressing roll pivotally hung and adapted to oscillate about the axis of the motor shaft, means 120 whereby said roll may oscillate on an axis at right angles to the motor axis to follow the contour of the floor independent of the movement of the truck, and means for transmitting power from said motor to said dressing roll.

7. In a surfacing machine, the combination 125 of a motor, a motor truck, a dressing roll pivotally hung and adapted to oscillate about the axis of the motor shaft, means whereby

said roll may be permitted to oscillate on an axis at right angles to the motor axis, means for preventing said oscillation, and means for transmitting power from said motor to 5 said roll.

8. In a surfacing machine, the combination of a truck, a motor carried by said truck, a frame pivotally connected to said truck, a dressing roll mounted in said frame 10 whereby said roll may have a vertical motion independent of that of said truck, means for driving said roll from said motor, means whereby the axis of the roll may swing out of a line parallel with the axis of the truck 15 wheels, and means whereby the roll may be raised from the floor when desired.

9. In a surfacing machine an operating roll, bearings supported to permit either or both ends of said roll to be independently 20 or jointly elevated or depressed to follow automatically the contour of the surface with uniform pressure, an abrasive covering detachably secured to said roll, a waste collector adjustably controlled by the bearings 25 of said roll, said collector having its bottom provided with a longitudinal slot from each edge of which extends an inclined shelf in close proximity to the surface of said roll, whereby the material removed from the surface 30 operated upon is deposited in the collector through the action of the air current created between said shelves and the rapidly revolving roll.

10. In a surfacing machine, an operating 35 roll, an abrasive covering detachably secured thereto, a waste collector adjustably controlled by the bearings of said roll, said collector being provided with a longitudinal slot through its bottom portion, a broad 40 shelf having an inclined surface extending back from a comparatively sharp floor engaging edge on each side of said slot, the surface of said shelf being in close proxim-

ity to the surface of the roll forming a comparatively restricted passageway, whereby a 45 current of air is produced to carry the material removed from the surface operated upon through said opening and deposit the same in the space behind said shelf.

11. In a surfacing machine, the combination of a rotatable dressing roll, a frame for said roll, a removable attachment to said frame, a longitudinally movable truck supporting a cross bar, said cross bar being adapted to support said removable attachment whereby the movement of said dressing roll over the surface to be finished may be controlled to produce a perfectly plane surface.

12. In a surfacing machine the combination of a truck, a motor driven dressing roll, a frame in which said roll is mounted, means whereby said roll may have a vertical motion independent of that of said truck, a vibratable spring bar attached to said 65 frame, and a weight adjustably mounted on said bar whereby said weight may be set to absorb or counteract the vibration of the dressing roll.

13. A surfacing machine comprising a 70 truck, a motor thereon, a swivel frame pivotally connected thereto, a surfacing roll mounted in said swivel frame whereby either or both ends of said roll may be freely elevated or depressed independently or simultaneously to automatically follow the contour of the surface with uniform pressure, and means for driving said roll from said motor.

In testimony whereof I affix my signature 80 in presence of two witnesses.

ALEXANDER BEVAN.
